SEWING GUIDE

Edward A. Little, Wolcott, Conn., assignor to The Rison Manufacturing Company, Naugatuck, Conn.

Filed Nov. 10, 1971, Ser. No. 197,635

Term of patent 14 years

Int. Cl. D3—99

U.S. Cl. D3—19 A

FIG. 2

FIG. 4

FIG. 1

FIG. 5

FIG. 3

FIG. 1 is a plan view of a sewing guide showing my new design, the other side being a mirror image thereof;

FIG. 2 is a top edge view;

FIG. 3 is a bottom edge view;

FIG. 4 is a side edge view as seen from the left of FIG. 1; and

FIG. 5 is a side edge view as seen from the right of FIG. 1.

I claim:

The ornamental design for a sewing guide, substantially as shown and described.
